(57) **ABSTRACT**

A piston for an internal combustion engine including a piston body (20). The piston body (20) defines a first cooling chamber (46) that is sealed closed and contains a first cooling medium (48) other than air. During operation of the piston, the first cooling medium (48) extracts heat from the surrounding regions of the piston body (20) to cool the piston body (20). The piston body (20) also defines a second cooling chamber (50) adjacent to the first cooling chamber (46). A cooling oil (51) is projected into the second cooling chamber (50) and against the portion of the piston body (20) separating the first and second cooling chambers (46, 50) to extract heat from the first cooling medium (48). The cooling oil (51) is redirected within the second cooling chamber (50) to extract additional heat from the first cooling medium (48) or directly from the piston body (20).

17 Claims, 3 Drawing Sheets

FIG. 1

FIG. 2

FIG. 3

1

PISTON INCLUDING A PAIR OF COOLING CHAMBERS

BACKGROUND OF THE INVENTION

1. Field of the Invention

The invention is related generally to pistons for internal combustion engines, and more particularly to pistons having internal cooling chambers for cooling the pistons during operation.

2. Description of the Related Art

It is desirable for engine manufacturers to increase the temperature of the combustion of the air/fuel mixture in the combustion chamber of the cylinder in order to increase the fuel efficiency of the engine and decrease emissions. Therefore, there remains a significant and continuing need for improved pistons with cooling systems capable of allowing the piston to withstand increased temperatures.

However, with increased heat of combustion, there is a corresponding need to design pistons that can operate in such an environment. One approach has been to cool the upper region of the piston that is exposed to the heat of combustion by forming an open or a closed cooling chamber in the piston and directing a stream of cooling oil from below into the chamber to help extract some of the heat of combustion from the affected regions of the piston. Such a cooling approach, however, has its limits and may not be adequate or most efficient under all conditions. Another alternative approach has been to encapsulate a cooling medium, such as sodium, within a sealed chamber in the upper portion of the piston as the principle means to extract the heat of combustion from the piston. This too has its limits and cannot always adequately cool the piston with ever-increasing combustion temperatures.

SUMMARY OF THE INVENTION

According to an aspect of the present invention, a piston for an internal combustion engine comprises a piston body having first and second cooling chambers. The first chamber is sealed closed and contains a first cooling medium other than air for extracting heat from the surrounding regions of the piston body during operation of the piston. The second cooling chamber is disposed adjacent to the first cooling chamber and is at least partially open to receive a flow of cooling oil during operation of the piston to extract additional heat from the piston body.

One advantage of such a piston is the ability to operate at increased combustion temperatures. In operation, both the first cooling medium in the first cooling chamber and the cooling oil in the second cooling chamber extract heat from the piston body to allow the piston to operate in the high temperature environment. Further, at least some of the cooling oil in the second cooling chamber is directed to the portion of the piston body separating the first and second cooling chambers to extract heat from the first cooling medium. In other words, the cooling oil extracts heat from both the piston body and the first cooling medium. Thus, the effectiveness of the first cooling medium is increased by the cooling oil.

Another advantage of such a piston is the substantially uniform cooling of the top of the piston body, which is directly exposed to the high temperatures from the combustion of the air/fuel mixture in the combustion chamber. The uniform cooling reduces thermal stresses within the piston body, thus increasing the operating life of the piston body. The uniform cooling is additionally advantageous when the

2

piston is employed in a diesel engine because hot spots in diesel engine pistons can lead to undesirable mono-nitrogen oxides (NO_x) generation.

According to another aspect of the invention, the first cooling medium in the first cooling chamber is of a material which is solid at ambient temperatures and melts at a predetermined temperature corresponding to an improved operating temperature of the engine. Such a fluid is advantageous because it allows the piston body to quickly warm to a more efficient operating temperature before the first operating medium melts and begins to cool the crown of the piston body in what is commonly referred to as the "cocktail shaker" effect. In other words, the time for the piston body to reach an increased operating temperature is reduced without compromising the cooling ability of the first cooling medium.

According to yet another aspect of the invention, the first cooling chamber is sealed closed, thus protecting the first cooling medium from contaminants and from oxidation, both of which could reduce the rate of cooling the piston.

BRIEF DESCRIPTION OF THE DRAWINGS

These and other features and advantages of the present invention will be readily appreciated, as the same becomes better understood by reference to the following detailed description when considered in connection with the accompanying drawings wherein:

FIG. 1 is a perspective and elevation view of the piston of the exemplary embodiment;

FIG. 2 is a cross-sectional view of the piston of the exemplary embodiment and taken along line 2-2 of FIG. 1; and

FIG. 3 is a perspective and elevation view, shown partly in section, of the piston of the exemplary embodiment.

DETAILED DESCRIPTION OF THE ENABLING EMBODIMENTS

Referring to the Figures, wherein like numerals indicate corresponding parts throughout the several views, a piston including a piston body 20 is generally shown in FIGS. 1-3. In the exemplary embodiment, the piston body 20 is for use in a compression-ignition, diesel engine block 22. However, it should be appreciated that the piston body 20 could be used in a wide range of other engines, e.g. spark-ignition gasoline engines.

As shown in FIG. 1, the piston body 20 includes a crown 24, generally indicated, disposed on an axis A and presenting a top surface 26. The top surface 26 has a flat outer periphery, which defines a bowl rim 28 and a combustion bowl 30 recessed from the bowl rim 28. The combustion bowl 30 defines a trough 32 having a generally circular shape and a bullet nose 34 extending axially upwardly from the trough 32. The crown 24 could be of one piece or multiple pieces joined together, for example, through welding, as will be appreciated by those skilled in the art. If the crown 24 is of more than one piece, then the pieces can be made of different materials. This could be advantageous because the portion of the crown 24 exposed to the combustion chamber of the cylinder could be of a more thermally resistant material, and the remainder of the crown 24 could be of a less thermally resistant material.

As shown in FIG. 1, the crown 24 defines a plurality of annular grooves 38 spaced axially from one another. As shown in FIG. 2, at least one piston ring 40 is disposed in each of the grooves 38 for sealing the crown 24 to the engine block 22. In operation, the top surface 26 of the crown 24 is generally the hottest portion of the piston body 20 because it is exposed to the combustion of the fuel/air mixture in the

combustion chamber of the cylinder. Therefore, the piston ring **40** which is closest to the top surface **26** can be of a material resistant to higher temperatures than the other piston rings **40**. However, the piston rings **40** could all be made of the same material. The exemplary embodiment includes three piston rings **40**; however, it should be appreciated that any desirable number of piston rings **40** could be employed.

In the exemplary embodiment, the piston body **20** is a monobloc piston body **20**, i.e. the piston body **20** includes a skirt **41** integrally formed with or secured to at least the bottom of the crown **24**. The skirt **41** could be secured to the crown **24** through friction welding, for example. Alternately, the skirt **41** could be hingedly connected to the crown **24** with a pin (not shown). In the exemplary embodiment, the skirt **41** has a generally cylindrical shape and extends axially downward from the bowl rim **28** of the top surface **26**. The skirt **41** presents a pair of diametrically opposed bosses **42** spaced axially from the piston rings **40**, and the bosses **42** are sized to receive a pin (not shown) to connect the skirt **41** to a piston rod (not shown), as will be appreciated by those skilled in the art.

As best shown in FIG. 2, the piston body **20** of the exemplary embodiment further includes a wall **44** extending from the side of the crown **24** to the underside of the combustion bowl **30** to define a first cooling chamber **46**. The first cooling chamber **46** is spaced radially inward of the piston rings **40** and axially below the bowl rim **28**. A first cooling medium **48** other than air is disposed in the first cooling chamber **46** for extracting heat from the surrounding regions of the piston body **20**. Specifically, in the exemplary embodiment, the first cooling medium extracts heat from the top surface **26** of the crown **24** and from the piston rings **40**. In operation, reciprocation of the piston body **20** within the cylinder of the engine block **22** causes the first cooling medium **48** to be shaken within the first cooling chamber **46** in what is generally known as the "cocktail shaker" effect. In other words, the first cooling medium **48** gets shaken up and down within the first cooling chamber **46** and extracts heat from the top surface **26** of the crown **24** with each collision against the top of the first cooling chamber **46**. Preferably, the first cooling medium **48** is disposed in approximately thirty to fifty percent of the first cooling chamber **46** to maximize the effectiveness of the "cocktail shaker" effect. By cooling the top surface **26** of the crown **24**, the first cooling medium **48** prevents oxidation of the bowl rim **28** and substantially equalizes the temperature around the circumference of the top surface **26** of the crown **24**.

In the exemplary embodiment, the first cooling chamber **46** is hermetically sealed closed, and therefore, the first cooling medium **48** is protected from contamination and from oxidation. It should be appreciated that the first cooling chamber **46** could take many different sizes and shapes other than those shown in the Figures. For example, the first cooling chamber **46** could be substantially disposed only adjacent to the bowl rim **28** of the crown **24**, or the first cooling chamber **46** could extend downwardly past each of the piston rings **40** for cooling all of the piston rings **40**.

Many engines, but particularly diesel engines, operate most efficiently at higher temperatures and pressures. In the exemplary embodiment, the first cooling medium **48** has a melting point temperature of between fifty and two hundred degrees Celsius (50-200° C.) to increase the efficiency of the engine. Most preferably, the first cooling medium **48** is of sodium or a sodium-based compound having a melting point temperature of approximately one hundred degrees Celsius (100° C.). In operation, the sodium **48** remains solid until it reaches the 100° C. melting point, i.e. after the piston body **20** has reached a more efficient operating temperature. Upon

reaching the melting point, the sodium **48** melts and the "cocktail shaker" effect described above begins to increase the cooling of the top surface **26** of the crown **24** and the piston rings **40**. Because this increased cooling only starts after the sodium **48** melts, the time that the piston **20** spends at the less efficient low temperatures is reduced. It should be appreciated that the first cooling medium could alternately be lithium, a lithium-based compound, silicone oil or any other cooling medium. It may be desirable to select the first cooling medium **48** as a function of the most efficient operating temperature of the piston **20**.

The piston body **20** further includes a second cooling chamber **50** adjacent to the first cooling chamber **46**. The second cooling chamber **50** is at least partially open to receive a cooling oil **51** into the second cooling chamber **50** during operation of the piston to extract additional heat from the piston body **20**. In the exemplary embodiment, the second cooling chamber **50** is defined by a flange **52** spaced axially from the wall **44** of the first cooling chamber **46**. In other words, the first and second cooling chambers **46, 50** are separated by the wall **44**. The flange **52** curves axially upward toward the top surface **26** of the crown **24** to an end that is axially below the combustion bowl **30** of the crown **24** to define a dish-tray shape, as best shown in FIG. 3. As best shown in FIG. 2, the second cooling chamber **50** is bounded on three sides by the flange **52**, combustion bowl **30** and the wall **44** and is open in the radial direction.

As shown in FIG. 2, the exemplary flange **52** defines a plurality of apertures **54**. A plurality of nozzles **56** are mounted on the engine block **22**, and each nozzle **56** is aimed to project the cooling oil **51** through an aperture **54** of the flange **52** whenever the piston body **20** is in a bottom-dead-center position. The nozzles **56** are fluidly connected to a fluid reservoir (not shown). In operation, the nozzles **56** project a cooling oil **51** through the apertures **54** of the flange **52** to collide with the wall **44** separating the enclosed and second cooling chambers **46, 50**. Heat is extracted from the first cooling medium **48** through the wall **44** to the cooling oil **51**. Thus, the first cooling medium **48** in the first cooling chamber **46** is cooled by the cooling oil **51**. The cooling oil **51** is then shaken within the dish-tray shaped second cooling chamber **50** through the "cocktail shaker" effect described above to extract additional heat from the piston body **20** and/or the first cooling medium **48**. The curvature of the flange **52** of the exemplary embodiment redirects some of the cooling oil **51** against the underside of the bullet nose **34** of the combustion chamber of the crown **24** to cool the top surface **26** of the crown **24**. Together, the first cooling medium **48** and the cooling oil **51** substantially uniformly cool the top surface **26** of the crown **24**. Eventually, the cooling oil **51** falls out of the second cooling chamber **50** and into the fluid reservoir (not shown). In the fluid reservoir, the cooling oil **51** may then be cooled and projected back against the wall **44** separating the first and second cooling chambers **46, 50** by the nozzles **56** in a closed-loop fashion. The cooling oil **51** could be an oil or any other desirable fluid.

Obviously, many modifications and variations of the present invention are possible in light of the above teachings and may be practiced otherwise than as specifically described while within the scope of the appended claims. In addition, the reference numerals in the claims are merely for convenience and are not to be read in any way as limiting.

What is claimed is:

1. A piston for an internal combustion engine, comprising: a piston body having a first cooling chamber that is sealed closed and which contains therein a first cooling medium other than air which is operative during opera-

- tion of the piston to extract heat from surrounding regions of said piston body;
- a second cooling chamber disposed adjacent said first cooling chamber and which is open in a radial direction to receive a flow of cooling oil into said second cooling chamber during operation of said piston to extract additional heat from said piston body, wherein said piston body defines a wall separating said first cooling chamber from said second cooling chamber for transferring heat from the first cooling medium contained in said first cooling chamber to the cooling oil received in said second cooling chamber; and
- a flange spaced from said wall to define said second cooling chamber, wherein said flange presents at least one aperture through which the cooling oil flows into said second cooling chamber during operation of said piston.
2. The piston as set forth in claim 1 wherein said piston body includes a crown and a skirt.
3. The piston as set forth in claim 2 wherein said first cooling chamber is disposed in said crown of said piston body.
4. The piston as set forth in claim 2 wherein said crown presents a top surface having a flat outer periphery to define a bowl rim.
5. The piston as set forth in claim 4 wherein said first cooling chamber is disposed in said crown adjacent to said bowl rim for extracting heat from said bowl rim of said piston.
6. The piston as set forth in claim 3 wherein said crown defines at least one groove extending circumferentially around said crown.
7. The piston as set forth in claim 6 further including at least one piston ring disposed in said groove of said crown.
8. The piston as set forth in claim 7 wherein said first cooling chamber is disposed in said crown adjacent to said groove for extracting heat from said piston ring.
9. The piston as set forth in claim 1 wherein the first cooling medium has a melting point of between fifty and two hundred degrees Celsius.
10. The piston as set forth in claim 9 wherein the first cooling medium has a melting point of approximately one hundred degrees Celsius.

11. The piston as set forth in claim 10 wherein the first cooling medium is sodium or a sodium-based compound.
12. A method of cooling a piston in an internal combustion engine, comprising the steps of:
- 5 providing a piston body including a first cooling chamber and a second cooling chamber adjacent the first cooling chamber, wherein the second cooling chamber is open in a radial direction to receive a flow of cooling oil into the second cooling chamber during operating of the piston, the piston body defines a wall separating the first cooling chamber from the second cooling chamber, and the piston body includes a flange spaced from the wall to define the second cooling chamber;
- 10 sealing a first cooling medium other than air in the first cooling chamber for extracting heat from the surrounding regions of the piston body; and
- 15 providing at least one opening in the flange defining the second cooling chamber for receiving the cooling oil into the second cooling chamber during operation to extract additional heat from the piston body.
- 20 13. The method as set forth in claim 12 including transferring heat from the first cooling medium to the cooling oil through the wall separating the first cooling chamber from the second cooling chamber.
- 25 14. The method as set forth in claim 12 further including the step of projecting the cooling oil into the second cooling chamber to extract heat from the piston body and the first cooling medium.
- 30 15. The method as set forth in claim 14 further including the step of redirecting the cooling oil in the second cooling chamber against the piston body to extract additional heat from the piston body and the first cooling medium.
- 35 16. The method as set forth in claim 12 further including the step of shaking the first cooling medium within the first cooling chamber to transfer heat from the piston body to the first cooling medium.
- 40 17. The method as set forth in claim 12 wherein the piston body includes a bowl rim and a plurality of grooves each supporting a piston ring and wherein the first cooling chamber is disposed adjacent to the bowl rim and the grooves for extracting heat from the bowl rim and the piston rings.
